2,686,330

BALL-ROLL VACUUM CLEANER

Nathaniel B. Wales, New York, N. Y., assignor to
Industrial Patent Corporation, New York, N. Y.

Application January 2, 1953, Serial No. 329,315

3 Claims. (Cl. 15—327)

1

This invention relates to an extremely easily movable vacuum cleaner and more particularly wherein the case enclosing the vacuum cleaner is formed as a revolvable hollow sphere.

The several operative components of the vacuum cleaner, such as the motor, turbo-fan and dust bag and controls therefore, are coordinated and sustained within the hollow sphere as a pendulum. The center of gravity of the motor and turbo-fan, the heaviest components, are positioned eccentric to the axis of the spherical casing and sustained by a supporting duct member journalled in two axial bearings which are formed in the diametrically opposite sides of the sphere. The axis of said supporting duct diametrically transverses the sphere to permit the spherical casing of the vacuum cleaner to roll on the floor as a ball, while the above-described components are pendulously sustained therein in a substantially stationary position due to the center of gravity of their weight being eccentric to the axis of the supporting duct member. However, the center of gravity is also positioned in a plane normal to said axis at its midpoint so that there is a positive pendulous bias tending to maintain the axis of rotation parallel to the floor. This pendulous assembly within the ball-like case eliminates all need for any moving joint in the suction line.

Thus, a pendulous weight, the vacuum cleaner components, is sustained within the sphere by bearings in its shell. The sphere, having substantially a single point of contact with the floor, results in a highly maneuverable vacuum cleaner.

Conventional cleaning tools connected with a conventional suction hose forms a suction communication through a bifurcated exterior duct member which in turn is secured to the above-mentioned supporting duct member, the ends of which extend exteriorly beyond the bearings journaling this duct in the shell of the sphere. The suction displacement then flows to the suction entry of the turbo-fan through a connecting passage between the supporting duct and the suction entry of the turbo-fan. The bifurcated duct secured to the ends of the supporting duct is normally maintained in a balanced position substantially parallel to the floor by the above-mentioned pendulous weight of the motor and turbo-fan and hence will not restrict the free movement of the rolling ball case.

The support-duct member within the spherical shell which acts as the pendulous support for the vacuum cleaner components may be journalled in ball or other low friction type of bearings

2

where it passes through the shell of the spherical case.

Means are provided to use preferably a paper disposable bag which is inserted through a door formed in the spherical shell and secured thereto by snap lock or other convenient means for easy access when it is desired to change paper dust bags. The open top of the paper bag is formed with a cardboard flap which maintains the bag normally closed by an elastic bias on the flap which, however, is displaced to an open position when the rigid cardboard head of the bag is inserted into a fixture formed as the terminus of the discharge duct from the turbo-fan within the spherical case of the vacuum cleaner.

When the paper bag is thus positioned to its fixture, the shutter is in open position. The relatively flexible body of the bag is supported on a platform which is biased by a predetermined spring tension whereby when the bag has received a specific weight of dirt as discharged from the turbo-fan, the added weight thereof overcomes said bias and opens the motor switch. It is evident that this switch actuation means also may close a circuit for a buzzer, light or other indicator to advise of its filled condition.

The objects of my invention are:

(1) A compact, highly maneuverable and low-cost vacuum cleaner.

(2) The suction-generating and dirt-collecting components of a vacuum cleaner entirely positioned within a hollow unitary sphere;

(3) Wherein the components of the vacuum cleaner, such as the motor, turbo-fan, dirt-collecting means and controls, are pendulously suspended within said hollow sphere;

(4) By a support shaft serving as a duct which is in open access to the suction of the turbo-fan.

(5) The hollow support shaft is journalled in two bearings secured to the wall of the sphere and formed on a line passing through the diametrical axis of the sphere to permit the sphere to rotate about the hollow support shaft as it is moved in respect to the floor.

(6) The center of gravity of the above-mentioned vacuum cleaner components so coordinated as to be eccentric to the above-mentioned hollow support shaft to maintain the components in a pendulously substantially stationary position in respect to the spherical casing. The center of gravity, however, remains in a plane normal to the diametrical axis at its midpoint so that there is a positive pendulous bias tending to maintain the axis of rotation of the sphere

parallel to the floor and thus defines the stability of the spherical case on the floor.

(7) The spherical casing is perforate to permit the filtered air to escape.

(8) The suspension shaft-duct to which the pendulous weight of the vacuum cleaner components are journalled within the sphere is formed where it extends through the sphere beyond its bearings as a bifurcated guide element and this bifurcated portion is normally substantially horizontal to the floor, maintained thus by the pendulous weight factor of the vacuum cleaner's components within the sphere.

(9) Means are provided to insert the dust bag and remove the same through a door formed in the hollow spherical shell.

Further objects of my invention are implicit in the accompanying specifications and drawings in which:

Figure 1 is a perspective view of the invention and illustrated as manipulated by an operator.

Figure 2 is an elevation with the sphere partially broken away looking through the diametrical axis on which the sphere revolves on the floor.

Figure 3 is a plan view, the sphere being broken away to show the co-ordination of the vacuum-producing and dirt-collecting components.

Figure 4 is a section of the spherical casing taken 90 degrees out of phase in respect to Figure 2 with interior ducts partially in section and showing in dotted lines the movement of the door segment of the spherical case.

Figure 5 is a perspective view of the top of the dirt-collecting bag showing in particular the cardboard facing connected to the bag and the hinged closure commanding an orifice in the cardboard facing.

Figure 6 is an enlarged fragment in elevation of the spherical case showing the locking means to lock the door in the sphere; also, the dirt-collecting bag in operational position.

Figure 7 is an exterior view in elevation of the spherical case showing a modification of the sphere to that extent wherein a narrow cylindrical mid-portion thereof normally contacts the floor.

Referring to the drawings in which similar elements are designated by similar numerals, numeral 1 is the unitary spherical case of the vacuum cleaner which for easy manufacturing and assembly purposes is formed of two semi-spherical portions, one section having an internal flange 35, seen in Figure 2, with which the other portion engages and the two semi-spherical portions are secured one to the other by screws 36. In a diametrical axis of the sphere 1, as seen in Figure 3, internally-formed flange members 23 in each hemispherical portion form suitable support means which center and engage ball bearings 22. Journalled in bearings 22 is the tubular shaft or duct member 6-6a which terminates at its respective ends exterior to sphere 1 into a bifurcated guide member 2, the bifurcated arms being designated as 2 and 2a. The guide member 2 may be suitably connected in any known manner to the duct member 6-6a. A conventional hose 3 is suitably secured to bifurcated member 2 at its mid-portion 2c, which in turn is connected to a staff 4 by which the operator manipulates suction nozzle 5, see Figure 1.

A partition 47, see Figure 3, formed in member 2, confines the suction flow of the suction-generating components in sphere 1 to duct 7 in the lower branch of the bifurcated member 2, as

seen in Figure 3, which in turn communicates with duct 8 in the 6a end of the tubular duct 6-6a. A partition 9 in the tubular member 6-6a guides the suction flow into the inlet 35 of turbo-fan 10, which is directly connected to motor 11, which is seen to be positioned in an extreme eccentric position in respect to the diametrical axis x-y of sphere 1 which also is the axis of journalled tubular shaft 6-6a. A discharge duct 12 from turbo-fan 10 rises within the sphere 1 across the diametrical axis of shell 1 and terminates in a flange 21 against which registers bag insert fixture 13 which is hinged to duct 12 at 14 which permits fixture 13 to pivot about 14 after latch 20 formed as a part of the upper portion of fixture 13 is disengaged from flange 21 so that the cardboard face 15 of dirt-collecting bag 16, see Figure 5, can be inserted into the recesses 49 formed in fixture 13, and then the fixture 13 may be moved about hinge 14 into a position as is seen in Figure 6, wherein the projecting finger 30 secured to duct 12 contacts flap or closure 17, displacing it to an open position through the medium of hinge 18 which may be biased to maintain closure 17 into a normal bag-closing position, as is seen in Figure 5. The discharge from turbo-blower 16 thus deposits the dirt content from suction nozzle 5 into porous bag 16, the air passing through the porous bag 16 and then issuing through orifices 34 in spherical case 1. The door 37 formed of a segment 40 of sphere 1 is hinged to sphere 1 at 38 and is retained in its closed position by the locking bar 42 which is secured to manual actuator 39 journalled in recess 41 of door 37. The locking bar 42 in its locking position engages stop 43 secured to sphere 1.

It is evident to those skilled in this art that the invention could be embodied in a vacuum cleaner assembly within sphere 1, wherein the suction flow of the turbo-fan could be conducted into the dirt bag 16 before the induced suction flow entered the turbo-fan.

A slightly modified spherical casing 1 is shown in Figure 7 and designated as 1a, wherein the mid-portion normal to the diametrical axis of the sphere may be flattened as at 44 to increase the stability of the sphere on the floor 46 beyond the sphere stabilizing bias factor as obtained by the center of gravity as seen at z in Figure 4 of the vacuum cleaner's assembly. The bag 16, preferably made of porous paper, see Figure 4, is supported on the table 28, which in turn is secured to pedestal 29. Pedestal 29 freely passes through the two walls of tubular support member 6 which act as a cross-head therefor. The lower end of pedestal 29 rests on spring-biased actuator 31 of microswitch 28 which controls the energization of motor 11 by supply cable 25 connected thereto. As dirt collects in bag 16, its accumulation increases the weight of bag 16, which increase of weight opens switch 28 through the increased pressure on its actuator 31. In this manner, indicating that the bag should be emptied or renewed. The extension of feed cable 25 after it passes through switch 28 is designated as cable 27, which is seen emerging from duct 24 in Figure 3, through grommet 33, and cable 27 may be of any suitable length, as is seen in Figure 1, terminating into a plug-in member insertable in any electric outlet panel.

The operation of the vacuum cleaner per se is too well known to recite here in detail, but it is evident from the drawings and specifications that a unitary spherical casing wherein the

vacuum-generating and dirt-collecting components of the cleaner are encompassed in a pendulous assembly, the pendulous action including the exteriorly positioned bifurcated guide member, form a vacuum cleaner having a maximum factor of maneuverability and ease of movement over rugs, carpets and thresholds, whereby the bifurcated guide member does not contact or dig into floor coverings as the sphere transverses the floor, its normal position being designated by the 10 dotted lines E—B in Figure 2.

What I desire to protect by United States Letters Patent is defined in the following claims:

1. A vacuum cleaner adapted to be rolled on the floor by forces exerted on its portable hose by the operator, comprising a substantially spherical hollow wheel, a horizontal transverse duct member positioned within said hollow wheel and emerging therefrom at two diametrically opposite points thereon, bearing means to journal said transverse member in said hollow wheel, vacuum generating means located within said hollow wheel and secured to said transverse duct member, dirt collecting means located within said hollow wheel and communicating with said vacuum generating means, the center of gravity of 20 said vacuum generating and said dirt collecting

means being below the axis of journalling of said transverse duct member at its mid-point, a guiding duct member exterior to said hollow wheel and secured to said transverse duct member at least at one exterior end thereof, said guiding duct member communicating with said vacuum generating means through the axis of said transverse duct member and terminating at its outer end at a point lying in the plane approximately normal to said axis of journalling at its mid-point, a vacuum nozzle, and a portable hose connecting said nozzle to said guiding duct member whereby to form a vacuum flow path from said nozzle to said dirt collecting means and said vacuum generating means.

2. A vacuum cleaner in accordance with claim 1 provided with perforations in said spherical hollow wheel.

3. A vacuum cleaner in accordance with claim 1, a door in said spherical hollow wheel giving access to said dirt collecting means.
